COMBINATION FOAM AND VACUUM CLEANER

William L. Petersen, Muskegon, Mich., assignor to Clarke
Floor Machine Company, Muskegon, Mich., a corpora-
tion of Michigan

Filed Jan. 18, 1960, Ser. No. 59,080

Term of patent 14 years

(Cl. D9—2)

FIG. 1

FIG. 2

FIG. 3

Fig. 1 is a perspective view of a combination foam and vacuum cleaner embodying my new design;

Fig. 2 is a side elevational view thereof on a reduced scale; and

Fig. 3 is a rear elevational view on a reduced scale.

I claim:

The ornamental design for a combination foam and vacuum cleaner, substantially as shown and described.
